Primary Examiner — Holly Bayham*Assistant Examiner* — Rhea Shields(74) *Attorney, Agent, or Firm* — Gardere Wynne Sewell LLP(57) **CLAIM**

The ornamental design for an ophthalmic lens edger, as shown and described.

DESCRIPTION

FIG. 1 is a front perspective view of an ophthalmic lens edger in accordance with the invention;

FIG. 2 is a front view of the ophthalmic lens edger shown in FIG. 1;

FIG. 3 is a rear view of the ophthalmic lens edger shown in FIG. 1;

FIG. 4 is a right side view of the ophthalmic lens edger shown in FIG. 1;

FIG. 5 is a left side view of the ophthalmic lens edger shown in FIG. 1;

FIG. 6 is a top view of the ophthalmic lens edger shown in FIG. 1; and,

FIG. 7 is a bottom view of the ophthalmic lens edger shown in FIG. 1.

In the drawings, the broken lines are for the purpose of illustrating environment only and form no part of the claimed design.
